(57) **CLAIM**

The ornamental design for a display screen or portion thereof with graphical user interface, as shown and described.

DESCRIPTION

FIG. 1 is a front view of a display screen or portion thereof with graphical user interface showing the new design.

FIG. 2 is a figure index of partial view FIGS. 2A and 2B showing the orientation of FIG. 2A with respect to FIG. 2B. FIG. 2A is a first partial front view of the display screen or portion thereof with graphical user interface of FIG. 1 displayed on and within a first example environmental structure of the display screen or portion thereof, as oriented in the figure index of FIG. 2.

FIG. 2B is a second partial front view of the display screen or portion thereof with graphical user interface of FIG. 1 displayed on and within a first example environmental structure of the display screen or portion thereof, as oriented in the figure index of FIG. 2.

FIG. 3 is a figure index of partial view FIGS. 3A, 3B, and 3C showing the orientation of FIG. 3A with respect to FIG. 3B and FIG. 3C.

FIG. 3A is a first partial front view of the display screen or portion thereof with graphical user interface of FIG. 1 displayed on and within a second example environmental structure of the display screen or portion thereof, as oriented in the figure index of FIG. 3.

FIG. 3B is a second partial front view of the display screen or portion thereof with graphical user interface of FIG. 1 displayed on and within a second example environmental structure of the display screen or portion thereof, as oriented in the figure index of FIG. 3.

FIG. 3C is a third partial front view of the display screen or portion thereof with graphical user interface of FIG. 1 displayed on and within a second example environmental structure of the display screen or portion thereof, as oriented in the figure index of FIG. 3.

FIG. 4 is a figure index of partial view FIGS. 4A, 4B, and 4C showing the orientation of FIG. 4A with respect to FIG. 4B and FIG. 4C.

FIG. 4A is a front view of the display screen or portion thereof with graphical user interface of FIG. 1 displayed on

(Continued)

and within a third example environmental structure of the display screen or portion thereof, as oriented in the figure index of FIG. 4.

FIG. 4B is a second partial front view of the display screen or portion thereof with graphical user interface of FIG. 1 displayed on and within a third example environmental structure of the display screen or portion thereof, as oriented in the figure index of FIG. 4; and,

FIG. 4C is a third partial front view of the display screen or portion thereof with graphical user interface of FIG. 1 displayed on and within a third example environmental structure of the display screen or portion thereof, as oriented in the figure index of FIG. 4.

All broken lines represent environmental subject matter, structure, and/or features that form no part of the claimed design. Specifically, the dash broken lines form portions the design that form no part of the claimed design, whereas the dot-dash lines depict the limits or boundary of the claim and likewise form no part of the claimed design.
